DISCHARGE DEVICE

August Gehrts, Berlin-Friedenau, Germany, assignor to Siemens & Halske Aktiengesellschaft, Siemensstadt, near Berlin, Germany, a German company

Application August 26, 1930, Serial No. 477,852
In Germany December 13, 1929

3 Claims. (Cl. 250—27.5)

This invention relates to discharge devices and more particularly to such devices in which the leading-in wires for the electrodes are embedded in a common vitreous stem or press.

- 5 It is necessary in discharge devices to seal electrode leading-in wires of different potentials through the wall of an evacuated or gas-filled glass vessel. This is the case, for example, in glow discharge lamps or in electron discharge devices having anode and cathode leading-in wires. In such instances, and particularly when the leading-in wires pass through a press or stem, a liberation of gas sets in when the stem is heated during the operation of the device, 10 which is to be traced to an electrolytic decomposition of the glass press or stem. This liberation covers the leading-in wires with a black or brown film according to the kind of glass used, such as lead or barium glass, respectively, 15 which may in time extend along the entire length of the leading-in wires and produce a leakage path between the external atmosphere and the inside of the vessel which allows a continuous seepage of air into the evacuated or gas-filled discharge tube. As is well known, the 20 composition of lead glass comprises silicates and lead oxide and the composition of barium glass comprises silicates and barium oxide. This decomposition, adjacent the leading-in wires, is 25 probably due to the fact that the anode and cathode leading-in wires are embedded in the stem or press relatively close to one another and an appreciable potential gradient is established therebetween. The decomposition is particularly active when the press or stem becomes heated to approximately 250° C.

It is an object of this invention, therefore, to prevent the decomposition of the vitreous press or stem adjacent the leading-in wires and to 30 prevent the subsequent seepage of air into the evacuated or gas-filled vessel.

In accordance with this invention, this object is attained by embedding the anode leading-in wire in the press or stem at a point outside the 35 electric field producing the electrolysis. The electric field is confined by placing a shield such as a wire, metal plate or the like in the stem or press between the anode leading-in wire and the adjacent cathode leading-in wire. This 40 shield is entirely sealed from the outside atmosphere and is electrically connected to the anode leading-in wire so that it has the same potential.

An embodiment of this invention is shown in the accompanying drawing which is a fragmentary view of an electron discharge device.

The anode leading-in wires 2 and 3 and the cathode K leading-in wires 4 and 5 are passed through a vitreous press or stem 1. A plurality of shields 6 and 6', each comprising a wire, metal plate or the like are disposed between each anode leading-in wire and the adjacent cathode leading-in wire. A conducting connection for the shields may extend through the press into the evacuated or gas-filled chamber of the vessel. The shields, however, should be entirely 10 encased by glass and should not project from the glass vessel on the surface exposed to the outer atmosphere.

The shields 6 and 6' may be connected with the anode in various ways as shown in the drawing. For example, the shield 6 is provided with a metallic connection which extends into the evacuated or gas-filled chamber of the vessel and is connected with the anode A externally of the press or stem. However, the shield, such as 6', may be completely embedded in the glass press or stem and electrically connected with the anode leading-in wire 3 inside the press or stem.

In devices of this construction, the electrolytic action occurs in the glass of the stem or press between the shields 6 and 6' having a potential the same as the anode and the adjacent cathode leading-in wires 4 and 5 respectively, and the electric field is therefore confined between the shield and the adjacent cathode leading-in wire leaving the anode leading-in wires in a portion of the stem beyond this field.

What is claimed is:

1. In a discharge device, a support, leading-in wires embedded in said support, and a conductive shield wholly embedded in said support intermediate certain of said leading-in wires, said shield being in contact with an adjacent leading-in wire.

2. In a discharge device, an enclosing vessel having a stem, leading-in wires embedded in said stem, and a shield wholly embedded in said stem intermediate certain of said leading-in wires, said shield being electrically connected to one of said leading-in wires adjacent thereto.

3. In a discharge device, an enclosing vessel having a stem, a cathode leading-in wire and an anode leading-in wire embedded in said stem, and a shield wholly embedded in said stem intermediate said leading-in wires, said shield being electrically connected to said anode leading-in wire.
